CLAIM

The ornamental design for a handle, as shown and described.

DESCRIPTION

FIG. 1 is a front perspective view of a handle showing, in particular, the ornamental design thereof.

FIG. 2 is a front view of the handle of FIG. 1.

FIG. 3 is a rear view of the handle of FIG. 1; and,

FIG. 4 is a left side view of the handle of FIG. 1, and the

right side view being a mirror image.

The broken line portions of FIGS. 1-4 are included to show unclaimed subject matter only and form no part of the claimed design.
